CLAIM

The ornamental design for a display screen or portion thereof with graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the U.S. Patent and Trademark Office file or records, but reserves all other copyrights whatsoever. The FIGURE is a front view of a display screen or portion thereof with graphical user interface showing our new design.

The outer perimeter shown in dashed broken lines in the FIGURE illustrates a display screen or portion thereof and forms no part of the claimed design.

The outermost broken line illustrates a display screen or portion thereof and the remainder of the broken lines illustrate portions of the graphical user interface. None of the broken lines form part of the claimed design.

The diagonal cross-hatched area within the left-hand side area of the graphical user interface illustrate a contrast of appearance and the icons atop the cross-hatching illustrate portions of the graphical user interface that form no part of the claimed design.
